UNITED STATES PATENT OFFICE.

ARTHUR J. HODGE AND HENRY B. RUGGLES, OF PASADENA, CALIFORNIA, ASSIGNEES
TO AMERICAN PRODUCTS COMPANY, OF ST. LOUIS, MISSOURI.

PULP GATHERING, TRANSFERRING, SQUEEZING, AND FORMING DEVICE.

1,249,088.

Specification of Letters Patent.

Patented Dec. 4, 1917.

Application filed February 10, 1915. Serial No. 7,301.

To all whom it may concern:

Be it known that we, ARTHUR J. HODGE and HENRY B. RUGGLES, citizens of the United States of America, residing at Pasadena, in the county of Los Angeles and State of California, have invented certain new and useful Improvements in Pulp Gathering, Transferring, Squeezing, and Forming Devices, of which the following is 10 a specification.

This invention has relation to certain new and useful improvements in pulp gathering, transferring, squeezing and forming devices and has for its primary object to provide 15 a device of this character in which the gathering and transferring plate will be adapted to reciprocate toward and away from the upwardly and spirally moving forms traveling through the pulp containing 20 tank to gather pulp from the tank and transfer same to said forms and press the pulp and squeeze the same against the outer faces of said forms as the gathering and transferring plates move in a horizontal 25 plane around the moving forms.

The invention has for another object, the provision of a series of circularly arranged arcuate pulp gathering and transferring plates within the pulp containing tank and 30 around the stationary shaft extended through said tank, to gather pulp and transfer the same to connected forms or former-sections movable spirally upon said shaft and through the tank, the arcuate pulp gathering and transferring plates also serving to 35 squeeze the pulp and force liquid from the same and compress said pulp upon said forms or former-sections.

Another object of the present invention 40 resides in the provision and arrangement of transversely curved and separated pulp gathering and transferring plates carried by a traveling ring gear encircling the stationary shaft and the moving forms upon 45 the same, and mechanism whereby alternate pulp gathering and transferring plates of the series may be forced inwardly toward the moving forms to transfer pulp to the latter and compress and squeeze said pulp 50 upon said forms while the remaining pulp gathering and transferring plates of the series are moving outwardly away from said moving forms to gather a fresh supply of pulp to be squeezed and pressed against

the moving forms upon the return or inward movement of the last mentioned pulp gathering and transferring plates as the first mentioned pulp gathering and transferring plates are withdrawn from the moving forms and move outwardly away from 60 the same.

The invention has for a further object, the provision of a pulp gathering, transferring, squeezing and forming device of this character in which the pulp gathering 65 and transferring plates will be provided with pulp gathering and transferring screens upon their concaved or working faces and will be mounted in such manner that as the plates move outwardly away 70 from the moving forms, the pulp gathered by the pulp gathering and transferring screens will be forced from the same toward the forms, thereby eliminating danger of the pulp adhering to the screens of the 75 plates and being drawn away from the forms by said screens.

The invention has for a still further object to provide improved and novel means for guiding the pulp gathering and transferring plates during the inward and outward movement of the same and at the same time gathering fluid from the tank during the inward movement of the pulp gathering and transferring plates and forcing said 80 fluid through said plates toward the moving forms during outward movement of said plates to force the pulp away from the working or concaved faces of said plates and toward the moving forms to prevent 85 the pulp transferred to and compressed around said forms by said plates from being drawn away from the forms by the plates as the latter move outwardly and away from said forms. 95

A still further object of the invention is to provide a pulp gathering, transferring, squeezing, and forming device of the above stated character which may be readily substituted for the primary pulp compressing 100 and squeezing mechanism and also the secondary compressing and squeezing mechanism of the machine as disclosed in our original and co-pending application, Serial Number 741 or of similar machines are employed in place of the device disclosed in our co-pending application Serial Number 2,051 or the device disclosed in our co-pend-

ing application Serial Number 4,035, if desired, the present device being an improvement over the second mentioned and the third mentioned applications as well as the referred to portions of the machine disclosed by our original and co-pending application Serial Number 741 the parts of said machine co-operating directly with said primary compressing and squeezing and said secondary compressing and shaping mechanism of the machine.

With these and other objects in view, our invention consists in the novel construction, combination and arrangement of parts as will be hereinafter more in detail described and the asserted novelty specifically pointed out in the claims.

Figure 1 is a vertical transverse section of the complete device in operation, parts of the device being in elevation and the section being substantially on the plane of line 1—1 of Fig. 2, looking in the direction indicated by the arrows;

Fig. 2 is a top plan view with the stationary central shaft and the drive shaft in section;

Fig. 3 is an enlarged fragmentary detail vertical section, on the plane of line 3—3 of Fig. 4; and

Fig. 4 is an enlarged fragmentary transverse horizontal section on the plane of line 4—4 of Fig. 3, looking in the direction indicated by the arrow.

Referring more particularly to the drawings in which similar reference characters designate corresponding parts throughout the several views, 1 designates the pulp containing tank which receives a continuous supply of pulp from a feed pipe 3 having its discharge end directed toward the open upper end of said tank 1, as in our co-pending applications Serial Numbers 741; 2051; and

In the present device, as in our original and co-pending application Serial No. 741 and our third and co-pending application Serial No. 4035, for similar devices, we employ a stationary central shaft 4, extended vertically through a central opening 5 in the bottom of the tank 1 and having a spirally extended feed and guide thread 8 formed thereon, preferably below said tank 1, to serve to feed and guide in an upward and spiral direction the forms or former-sections A, through the upwardly flared pulp receiving and directing receptacle 6 and through the tank 1, and around said stationary central shaft 4.

The receptacle 6 is preferably of the form shown in our previously mentioned co-pending applications and is extended upwardly from the edge of the opening 5 in the bottom of the tank 1 and is spaced from the stationary shaft 4; and it will be understood that this receptacle 6 may be of any suitable size and secured to the bottom of

the tank 1 in any preferred or well known manner. It will also be understood that the forms or former sections A should include outer screens 20 and interior central guide nuts 9 for movement over the spirally extended feed and guide thread 8, as shown in the drawings, and should be adapted to be securely locked together by some suitable and well known means (not shown). The remainder of the forms or former-sections A may be of the construction shown and described in our original and co-pending application Serial Number 741 or of any other suitable construction, and therefore further detail description of the forms or former-sections A, in this application, is believed to be unnecessary. It is also believed to be unnecessary to show or describe in this application, any means for rotating the forms or former-sections A, as they may be operated by the sectional former rotating mechanism disclosed in said co-pending application Serial Number 741 or by any other suitable means operatively connected with the drive pinion 63 mounted upon the drive shaft 64, below the tank 1. This drive shaft 64 extends vertically through said tank 1 and corresponds to the vertical drive shaft disclosed in said co-pending application Serial Number 741.

In the present invention we employ pulp gathering and transferring arcuate or transversely curved plates 21, formed preferably of perforated metal and having pulp gathering and transferring screens 22 mounted upon their working or concave inner faces, for gathering pulp from the pulp containing tank 1 and transferring said pulp to the moving forms or former-sections A and partially compressing the same upon said forms or former-sections A, as the latter pass upwardly in a spiral direction through said tank 1 and the plates 21 move inwardly and outwardly and travel around said forms or former-sections A, as will be later clearly understood.

The pulp gathering and transferring plates 21 are of substantially rectangular form in general outline and are arranged in a circular series within the pulp containing tank 1 and around the stationary central shaft 4 and the moving forms or former-sections A traveling upon the latter.

The upper or extended ends of the pulp gathering and transferring plates 21 project above the pulp level line B and said plates 21 are preferably in different horizontal planes so that the upper and lower edges of the various plates 21 are offset from one another to prevent the creation of joints or seams in the pulp transferred to and compressed around said forms or former-sections A by said plates 21.

The pulp gathering and transferring plates 21 form the end or head plates of the

reciprocating cylinder heads 23. Each reciprocating cylinder head 23 has a continuous flange 24 formed around its open inner end, around which flange 24 is secured one end of a bellows 25, the opposite end of which is secured around a stationary inner cylinder head 26, mounted in a suitable manner upon a casting 27 which in turn is mounted upon a supporting shaft 28.

10 Each casting 27 is secured to an external gear ring 29 by means of screws 30 or other suitable securing members passed through an upwardly directed flange 31 formed on an extension 32 of said casting, said securing members 30 also being extended into the external ring gear 29, against the inner smooth face of which said flange 31 is engaged. The external ring gear 29 rides upon the lower arms 33 of the supporting brackets 34 secured to the inner face of the pulp containing tank 1 and displacement of the external gear ring 29 is prevented by the upstanding centering lugs 35 formed on said lower arms 33. The external ring gear 29 is rotated 20 upon the supporting arms 33 by means of a drive pinion 36 keyed upon the drive shaft 64 and meshing with the teeth of said external ring gear 29 to carry the supporting shafts 28 and parts mounted thereon around 25 the moving forms or former-sections A and in the direction of rotation of the forms or former-sections A.

The castings 27 are connected and braced by the ring 37 engaged in the bearing ears 38 which project outwardly from the upper portions of the castings 27, as will be readily understood by referring to the drawings, and as the external ring gear 29 is rotated to carry the supporting shafts 28 and the 30 castings 27 and parts mounted upon the same around the moving forms or former-sections A, said supporting shafts 28 are caused to rotate within the castings 27, by means of the driven pinions 39 keyed upon 35 said supporting shafts 28 and meshing with the teeth of the stationary internal gear ring 40. Suitable securing members 41 are employed to secure the stationary internal gear ring 40 to the ends 42 of the upper arms 43 40 of the castings 34, previously mentioned.

The opposite ends of the supporting shafts 28 are extended beyond the castings 27 and have mounted thereon, the rigid cam disks 44, from which project the eccentric pins 45. 50 Loosely mounted upon each eccentric pin 45 is a collar 46, which is prevented from working off of the same, by means of a suitable pin 47 passed transversely through said eccentric pin 45. Each collar 46 is provided 55 with a pair of ears 48, between which is pivoted one end of a pitman arm 49, by means of a pivot pin 50 passed through the same and through said ears 48.

The opposite end of each pitman arm 49 60 is pivoted between a pair of ears 51 of a col-

lar 52, by means of a suitable pivot pin 53. The collars 52, however, are loosely mounted upon the upwardly and downwardly extended pintles 54 projecting from the top and bottom faces of the reciprocating cylinder head 23 opposite and connected with the casting 27 above and below which said pitman arms 49 are positioned. The collars 52 are prevented from working off of the pintles 54 by suitable pins 55 passed transversely through the ends of said pintles 54.

It will be readily seen that upon rotation of the supporting shafts 28, the pitman arms 49 will be operated to reciprocate the reciprocating cylinder heads 23 and move the 70 pulp gathering and transferring plates 21 with their screens 22 toward and away from the moving forms or former-sections A. The reciprocating cylinder heads 23 are guided in their movements with respect to the forms 75 or former-sections A and the castings with which said reciprocating cylinder heads 23 are connected, by means of upper and lower guide arms 56 sliding in the guideways 57 formed on extended upper and lower portions of the castings 27. The guide arms 56 project radially from the collars 58 which are non-rotatably mounted upon the pintles 54, inwardly of the collars 52, thereby preventing the reciprocating cylinder heads 23 90 from turning to one side during operation of the device.

While any suitable number of castings 27 and reciprocating cylinder heads 23 with the screen covered pulp gathering and transferring plates 21 may be employed, we prefer to use an even number of the same, as shown in the drawings, with the reciprocating cylinder heads 23 connected with the cam disks 44 by means of the pitman arms 95 49 in such manner that while alternate reciprocating cylinder heads 23 are in their innermost positions with the screens 22 of the pulp gathering and transferring plates 21 engaged against the pulp around the 100 moving forms or former-sections A, the remaining reciprocating cylinder heads 23 are in their outermost positions, as will be readily understood by referring to Fig. 2 of the drawings. It will therefore be evident 105 that as one set of pulp gathering and transferring plates 21 moves outwardly away from the moving forms or former-sections A to gather a fresh supply of pulp to be transferred to said moving forms or former-sections A, the remaining set or alternate pulp gathering and transferring plates 21 move 110 inwardly to deposit a fresh supply of pulp upon the outer screens or faces of said moving forms or former-sections A.

As each pulp gathering and transferring plate 21 travels around the moving forms or former-sections A and at the same time moves inwardly toward said forms or former-sections A, it gathers pulp from the 115 120 125

5 tank 1, upon the outer face of the screen 22 upon the concave or working face of said pulp gathering and transferring plate 21, and then transfers this pulp to the outer 10 face of said moving forms or former sections A, liquid from the pulp passing through the screen 22 and through the perforations of the pulp gathering and transferring plate 21, into the bellows 25. After 15 the pulp has been transferred to the outer face of the moving forms or former-sections A from the screen 22 and partially or completely compressed upon said forms or former-sections A by said screen 22, the latter together with the pulp gathering and transferring plate 21 and the complete reciprocating cylinder head 23, moves outwardly as it continues its movement around said moving forms or former-sections A and 20 during this outward movement of these parts of the device, the bellows 25 serves to force outwardly the liquid gathered therein, through the perforations of the pulp gathering and transferring plate 21 and its screen 22 and toward the moving forms or former-sections A, thereby forcing the pulp away from the screen 22 and against the moving forms or former-sections A and preventing this pulp from being again drawn away 25 from said forms or former-sections A by the receding pulp gathering and transferring screen 22 and plate 21.

30 By referring to Fig. 3 of the drawings, it will be seen that the upper guide arm 56 normally rests in the bottom of the upper guideway 57 while the lower guide arm 56 is suspended in the lower portion of the lower guideway 57. This will permit an upward movement of the reciprocating cylinder heads 23 and the pulp gathering and transferring plates 21 and screens 22 carried by the same when said screens 22 are engaged against the pulp deposited and compressed upon the moving forms or former-sections A, thereby making it possible for said screens 22 to move in a spiral direction with said forms or former-sections A while depositing and compressing pulp upon the same.

35 50 From the foregoing description taken in connection with the accompanying drawings, it is believed that the construction and operation of the complete device will be readily understood and that it will be apparent that the present device will produce a continuous output free of seams, and it is thought that a further detailed description of the device is unnecessary.

55 60 While the preferred embodiment of our invention has been shown and described, it will be understood that the form of the pulp gathering and transferring members may be varied at will and caused to perform the complete compressing operation or only a 65 part of the same as desired and many minor

changes in the details of construction and arrangement of parts may be resorted to within the scope of the appended claims.

What is claimed is:—

1. In a device of the class described, the 70 combination with a revoluble form; of reciprocating pulp gathering and transferring members operating on portions of the form's surface progressively.

2. In a device of the class described, the 75 combination with a pulp receiving form; of reciprocating members around said form for gathering pulp and transferring the same to said form as it passes between said members and means for moving the said form between 80 said members.

3. In a device of the class described, the 85 combination with a pulp containing tank and a pulp receiving form movable endwise through said tank; of pulp gathering and transferring plates within said tank, and means for operating said pulp gathering and transferring plates to gather pulp from said tank and transfer the same to said form while it is in motion.

90 4. In a device of the class described, the combination with a pulp containing tank, a stationary guide shaft extended through said tank, and forms movable spirally upon said shaft and through said tank; of pulp 95 gathering and transferring plates within said tank and movable around and toward said forms to gather pulp and transfer the same to said forms.

5. In a device of the class described, the 100 combination with a pulp containing tank, connected forms movable through said tank, and means for supporting and guiding said forms; of pulp gathering and transferring plates within said tank and around said forms, screens upon the working faces of said plates, means for supporting said plates, means for moving said plates around said forms, and means for reciprocating said plates toward and away from said forms.

105 6. In a device of the class described, the combination with a pulp containing tank, a shaft extended through said tank and connected forms movable upon said shaft; of a traveling ring gear, a stationary ring gear, 115 means for supporting said ring gears, castings carried by said movable ring gear, stationary cylinder heads carried by said castings, reciprocating cylinder heads opposite and connected with said stationary cylinder heads, a drive shaft, a drive pinion carried by said drive shaft and engaged with said traveling ring gear to operate the latter, means operatively connected with the reciprocating cylinder heads and with the stationary ring gear to operate said reciprocating cylinder heads, and pulp gathering and transferring plates carried by and forming a part of said reciprocating cylinder heads.

120 125 130 7. In a device of the class described, the

combination with a pulp containing tank, a stationary guide shaft extending through said tank, and a pulp gathering and directing receptacle surrounding a portion of said stationary guide shaft; of connected forms movable upon said stationary guide shaft and through said pulp gathering and directing receptacle and said tank, pulp gathering and transferring plates for gathering pulp and transferring the same to said forms, screens carried by said plates, means for forcing said plates and screens toward said forms and drawing the same away from said forms, and means for forcing the liquid in one direction through said plates and screens during movement of the same away from said forms.

8. In a device of the class described, the combination with a pulp containing tank; of connected forms movable through said tank, perforated pulp gathering and transferring plates within said tank, screens carried by said plates, means for reciprocating said plates toward and away from the moving forms, means for guiding said plates during their reciprocating movement and permitting a limited upward movement of the same when in their innermost positions, means for forcing liquid through said plates and screens in a direction toward said forms during movement of said plates and screens away from said forms, and means for moving said plates and screens around said forms.

9. In a device of the class described, the combination with a pulp containing tank; of a form movable through said tank, transversely curved pulp gathering and transferring plates within said tank and arranged in varying horizontal planes around said forms, screens mounted upon the concave faces of said plates, means for moving said plates around said forms, and means for recipro-

cating said plates toward and away from said forms.

10. In a device of the class described, the combination with a traveling form; of material gathering and transferring members movable toward and away from said form as it passes them.

11. In a device of the class described, the combination with a traveling form; of reciprocating material receiving and transferring members opposite and coöperating with said form as the said form is moving between the said members.

12. In a device of the class described, the combination with a form, of material gathering and transferring members adjacent the same and arranged to bear on different longitudinal portions of said form, whereby their extremities are not in the same planes.

13. In a device of the class described, the combination with a form, having an endwise and a rotary movement, of concave material receiving and transferring members coöperating with said form and means for moving said members toward and away from said form, the movement of said members not interfering with the movement of the form between them.

14. In a device of the class described, the combination with a central form; of reciprocating material gathering and transferring members arranged concentrically around said form and reaching to different distances on the form whereby their ends are in various horizontal planes, and means for operating said members.

In testimony whereof we affix our signatures in presence of two witnesses.

ARTHUR J. HODGE.
HENRY B. RUGGLES.
